UNITED STATES PATENT OFFICE.

ALEXANDER E. SORUM AND ROBERT T. BROCKMAN, OF TERRE HAUTE, INDIANA,
ASSIGNORS TO INTERNATIONAL MONEY MACHINE COMPANY, OF TERRE HAUTE,
INDIANA.

COIN-COUNTING DEVICE FOR MONEY-PAYING MACHINES.

Application filed May 15, 1914, Serial No. 494,887. Renewed August 22, 1921.

To all whom it may concern:

Be it known that we, ALEXANDER E. SORUM, a citizen of the United States, residing at Terre Haute, Vigo County, and State of Indiana, and ROBERT T. BROCKMAN, a citizen of the United States, residing at Terre Haute, Vigo County, and State of Indiana, have invented and discovered certain new and useful Improvements in Coin-Counting Devices for Money-Paying Machines, of which the following is a specification.

Our invention relates to coin counting devices for money paying machines.

The object of the invention is to enable the number of coins of different denominations required to supply the money for a pay roll to be determined prior to the supply of such coins to the machine from which they are to be distributed.

Our invention is adapted to be applied as an attachment to that type of machines in which an adding machine is employed in connection with means adapted to selectively discharge coins from groups of different denominations into suitable receptacles by the actions of adding up different amounts to be paid, on the key board of the adding machine, and actuating the handle thereof in the usual manner to effect the registration.

In a machine of this character, a series of tubes or similar holders is provided in connection with the adding machine in which holders are placed coins of different denominations, and between these coin holding means and the adding machine there is provided a selective ejecting mechanism whereby coins of the desired denomination and to the required number are ejected from the coin holders. In our invention it is the aim to enable the number of coins that may be required in each coin holder for the settlement of the amounts to be calculated on the adding machine, to be predetermined so that the required number of coins may be procured in advance ready to be supplied to the coin holders previous to paying out the sums of money required to settle a pay roll.

With these objects in view our invention is embodied in preferable form in the device hereinafter described and illustrated in the accompanying drawings.

In these drawings, Figure 1 is a top plan

view partly broken away, of an adding machine, a part of the ordinary construction used in a money paying mechanism adapted to be employed in connection with such adding machine and also showing our invention applied to the latter mechanism in place of the usual coin holders; Figure 2, an enlarged top plan view of the attachment employed in our invention, with the casing partly broken away to show the interior registering wheels of one set of coin indicating means; Figure 2^a is a fragmentary sectional view showing more clearly the connecting means intermediate the handle shaft of the adding machine, the ejector shaft, and the ejectors; Figure 2^b is a fragmentary view in section also depicting more fully the mounting of the ejectors in respect to the ejector arms on the ejector shaft and in relation to the selectors; Figure 3 is a section on the line a—a of Figure 2; Figure 4 is a section on line b—b of Figure 2; Figure 5 a section on the line c—c of Figure 2; Fig. 6 is a section on the same line as Figure 5, showing the carrying operation completed; Fig. 7 is a section on the same line as Figures 5 and 6 and showing the mechanism in position ready to be re-set for the purpose for carrying the registering wheels to zero, and Figure 8 is an enlarged detail view of part of the means for supporting the attachment carrying the mechanism embodying our invention.

Referring to the drawings, 1 indicates the key-board of an adding machine of any usual type and 2 is the operating handle thereof by the manipulation of which the amounts added on the machine are adapted to be registered and in some cases recorded. In the usual money-paying machine, the mechanism of the adding device is selectively connected to a series of ejector rods 3, which in this case constitute the main operating members for the counting device and which are suitably mounted on a supporting base 4. In the usual money-paying machine each of these rods is adapted to correspond to a tube which is adapted to hold a number of coins of a single denomination and from which separate tubes the respective rods are adapted to eject the coins for the purpose of completing the sum of money totaled in the adding machine for each pay-

As seen in Figure 2^a, the handle shaft 50 of the adding machine has a spring actuated double armed lever 51 fixed thereon a stud 52 on one arm of said lever 51 engaging the bifurcated end of a rock arm 53 suitably journaled in the frame or casing of the adding machine. The axis of the arm 53 carries a second arm 54 projecting upwards and having a stud 55 adapted to be engaged by a hook 56. The hook 56 is pivotally mounted on an arm 57 rigidly attached to the ejector shaft 58 from which project downwardly the various ejector arms 59 seen in Figure 1. Thus it is that each time the shaft 50 is operated owing to the movement of the handle 2 a rocking movement is imparted to the arms 53 and 54 and such movement is communicated to the ejector shaft arm 57 thereby partially rotating the ejector shaft 58 with its arms 59. As seen in Figure 2^b, bails 60 are disposed adjacent the ejectors or rods 3 and these bails are susceptible of actuation by selector 61 disposed above the same. Movement of the selectors imparting pivotal movement to predetermined bails 60 and each bail having one of its sides engaging a rod 3 to thereby throw the rod laterally at its rear end and cause engagement of a projection on said rear end, with the lower end of an ejector arm 59. This general cooperation of parts is not material to the invention for the reason that we contemplate using any suitable mechanism for effecting the proper selection of the various rods 3 preliminary to movement of the rods by the handle 2 and shaft 50. Each of the rods 3, of course, as will be understood more fully hereinafter, is an actuating member adapted to cooperate with a register disposed at its front end, to operate the register each time the rod is reciprocated in an operation of the adding machine by the handle 2.

In our invention a register comprising a series of registering wheels is employed for each operating rod 3 for the purpose of counting the total number of coins required for the holder corresponding to said rod. These sets of wheels are enclosed within and mounted on a detachable casing comprising a back plate 5, side plates 6 and 7 and top plate 8, this latter plate being provided with sight openings through which the numbers on the registering wheels of each series are adapted to be read. The rear plate of the casing is provided at its lower part at each corner with lugs 9 which are adapted to be hung on studs 10 projecting from the main base 4 of the machine and at its upper corners the back plate is also provided with hooks 11 each adapted to engage a latch 12 which may be also connected with the base 4 of the machine. By this arrangement the casing is made attachable to and detachable from the body of the paying machine proper

and is designed to take the place of the usual coin tray or similar holding device employed in such machines and when in place the series of registering wheels in the attachment are adapted to be positioned opposite the respective operating rods 3. It is obvious that any suitable form of registering mechanism may be employed in connection with each operating rod. We have shown and described a particular form of mechanism for this purpose which is especially suitable for use to accomplish the purposes of this invention.

Referring to the construction of one of the sets of registering mechanisms, 13 is a rotatable shaft mounted in the side plates 6 and 7 of the casing and provided with a handle 14 at the left hand end thereof, which handle serves to enable the registering wheels to be re-set to zero after the counting operation has been completed. Extending forwardly from the back plate 5 of the casing is a horizontal supporting plate 15, carrying a stud 16 on which is mounted a slide bar 17, provided with slots 18 to engage the studs. This slide bar is provided with a depending lug 19 with which is adapted to engage the main operating member 3 whereby the slide bar is pushed outwardly toward the front of the machine when the rod is operated. A return spring 20 serves to return the slide bar to its inward position. Extending upwardly from the slide bar is an arm 21 which is provided with a pin 22 engaging a slot in a disk 23 which is mounted loosely on the shaft 13. This disk 23 constitutes the main rotatable operating member for the registering wheels and it is provided on its inner face with pawls 24 pivoted on studs 25 projecting from the inner surface of the member 23. These pawls are adapted to engage the teeth of a ratchet wheel 26, loosely surrounding the shaft 13 and fixed to the outer face of a units number wheel 27. When the rod 3 is reciprocated these pawls are adapted to turn the ratchet wheel and the number wheel attached thereto in a step by step movement. Springs 28 bearing against studs 29 serve to hold the pawls in engagement with the ratchet teeth. The number wheel 27 is retained in indexed position by detent spring 30 which engages a recess, there being a number of such recesses formed at intervals on the periphery of the said number wheel.

On the inner face of the number wheel 27 is a stud 31 on which is mounted a pawl 32 which is adapted to engage the teeth of the ratchet wheel 33 which corresponds with the ratchet wheel 26 of the units wheel. The ratchet wheel 33 is fixed to the outer face of a tens number wheel 34. Between this ratchet wheel 33 and the inner face of the units wheel is a cam 35. This cam is fixed to the shaft 13 by means of a key 36 and a

portion of the pawl 32 is adapted to ride upon the surface of this cam. When the pawl reaches the cut away portion 37 of the cam the former will be permitted to fall into engagement with the teeth of the ratchet wheel 33, but when riding upon the high part of the cam, the pawl will be carried out of engagement with the said teeth. This pawl is adapted to bear upon the low part of the cam so as to engage the ratchet and turn the same the space of one tooth at the time when the units wheel has completed nine-tenths of a revolution and the ten is to be carried over to the tens wheel. The high part of the cam serves to hold the pawl out of engagement with these teeth until this point is reached. A spring 38 serves to press the pawl 32 into mesh with the ratchet teeth and against the cam.

The cam is provided with an outwardly projecting tooth 40 over which is adapted to hook the projecting forward lug of the pawl 32, whereby when the cam 35 is turned rearwardly, or in the direction of the arrow shown in Figure 7, the pawl 32 is carried backwardly, carrying with it the number wheels, so as to re-set them in zero position. The shaft 13 is provided with a detaining lug 41 having a groove which is engaged by the end of a sliding latch 42, provided with a spring 43. This latch serves to yieldingly retain the shaft in its normal position. A stop pin 44, mounted on the left hand plate 7, serves to engage the lug 41 on the shaft and is so located as to limit the movement thereof to nine-tenths of a complete revolution. The mechanism of each set is provided with a hundreds number wheel 45 and a thousands wheel 46, each of which is adapted to be operated by carrying mechanism of the same construction as that described with respect to the tens wheel.

In the operation of the device the coin holding means are removed from the base and the casing containing the attachment embodying our invention substituted therefor. As the keys of the adding mechanism are struck and the handle of the machine turned the operating rods corresponding to the respective denominations of coins will be reciprocated and the number of the coins of each denomination called for by the sums calculated on the adding machine will be registered by the respective sets of registering means, thus serving to count the number of coins required for each holder.

As the rod 3 of any set is pushed in, it will strike the lug 19 of the bar 17, sliding the latter which turns the rotatable operating disk 23, carrying the pawls 24 which pawls by their engagement with the ratchet wheel 26, serve to turn the units number wheel 27. As the numeral 9 on this wheel reaches the sight opening, the pawl 32 carried by said units wheel will ride on the low part of the fixed cam 35, and thus drop into engagement with the ratchet teeth 33 of the tens wheel. As the two number wheels move together to their next position, the tooth of the pawl 32 will be carried over the hook 40 of the cam in position to enable the pawls and number wheels to be re-set, by the turning of the shaft 13, and at the same time the pawl will bear on the high part of the cam and thus be lifted out of engagement with the ratchet wheel.

Each set of registering wheels is operated in the same manner. When the count has been completed all the wheels of the various sets are turned back to zero by means of the handle 14 and shaft 13.

Having thus described our invention, what we claim is:

1. In calculating mechanism of the class described, the combination of a support, a shaft mounted thereon, a plurality of registers carried by the shaft, each register including an operating disk and wheels adapted to be actuated from said disk, a spring retracted slide bar associated with each register and having connection with the disk of such register, and an operating member co-acting with each slide bar aforesaid to cause accumulating action of the registers.
2. In a calculating machine, the combination of a support, a shaft mounted thereon, registers carried by said shaft and each composed of units and tens registering wheels, operating means for the units wheel of each register, a lug projecting from the shaft, a stop mounted on the support, means for turning the shaft for zeroizing purposes, limiting the shaft to nine-tenths of a revolution by reason of the cooperation of the said lug with said stop, and detent means for holding the shaft in a predetermined position and cooperative with said lug, said detent means consisting of a spring actuated latch.
3. In a calculating device of the class described, the combination of a support, a shaft mounted thereon, a plurality of registers carried by said shaft and including an operating disk and registering wheels associated therewith, actuating mechanism for each register including a bracket on said support, a slide bar carried by said bracket, a spring connecting said bar with the support to hold the coacting register disk in a normal position, a pin and slot connection intermediate said slide bar and the associated disk of a cooperating register, an operating member adjacent to the slide bar, said slide bar being formed with an offstanding projection engageable by said operating member upon movement of the latter.
4. In combination with an adding machine, a series of reciprocable rods each corresponding to a coin denomination, and selectively operable by said adding machine,

and separate means for each rod registering the movements thereof, each of said registering means including a movable part operable by its respective rod, a casing in which said sets of registering means are mounted, and means to removably position said case relatively to said rods, substantially as described.

In witness whereof, we have hereunto set

our hands and seals at Terre Haute, Vigo County, Indiana this 11th day of May, 19 A. D., nineteen hundred and fourteen.
